UNITED STATES PATENT OFFICE.

ERNEST G. ELDRIDGE, OF ALHAMBRA, CALIFORNIA.

INDEXING MECHANISM FOR PERMUTATION-LOCKS.

1,254,783.

Specification of Letters Patent. Patented Jan. 29, 1918.

Application filed January 20, 1917. Serial No. 143,498.

To all whom it may concern:

Be it known that I, ERNEST G. ELDRIDGE, a citizen of the United States, residing at Alhambra, in the county of Los Angeles, State of California, have invented new and useful Improvements in Indexing Mechanism for Permutation-Locks, of which the following is a specification.

This invention relates to devices for indexing permutation locks and the like; and a primary object of this invention is to provide an accurate indexing mechanism in simple form and capable of quick and simple operation. It is also an object of this invention to provide an indexing mechanism which may be attached to any kind of a permutation or combination lock and attached to any kind of exterior plate or escutcheon of such a lock; without any material changes or alterations in the lock itself, or in the exterior plate or escutcheon thereof. And it is also an object of this invention to provide an indexing mechanism which may be fully and quickly operated by sense of touch and with the use of a single hand. Heretofore, indexing mechanisms which have been provided with means for indicating or counting in larger units than single spaces or single positions, at the will of the operator, have usually required the use of both hands for their manipulation. And it is an object of this invention to provide such an indexing mechanism (one operated by sense of touch) capable of operation by use of a single hand.

My preferred form of indexing mechanism, according to my invention, is made to be contained within an indexing knob, which of course, with a suitable lock, may also serve as a door knob. It will be understood, however, that this location of indexing mechanism is not an essential of my invention broadly considered, but is a preferred feature thereof. The essentials of my invention may be said to include a plurality of notched or equivalent members and a coöperating means adapted to coöperatively engage any of the notched members, but only one at a time: more specifically, a plurality of notched or equivalent members lying transversely alongside each other, being preferably circular in formation and lying in parallel planes about a common axis; and a relatively transversely movable

or adjustable member adapted to coöperate with any one of the notched circular members, but only to coöperate with one of said members at any one time. The relatively transversely movable member may be moved to coöperate with any one of the circular members; and relative rotation (that is, relative as between the circular notched members and the transversely movable member) will cause the coöperating members to indicate the amount of rotation in terms of the spacings of the notches in the circular member then being in coöperation with the other member. These circular notched members may be in the form of disks, or, as in my preferred construction, are in the form of rings with the notches on their inner peripheries. These notched rings, in my preferred construction, are mounted on the inside of a hollow knob; and the coöperating relatively transversely movable member is mounted upon a stationary part which is preferably mounted upon the front plate or escutcheon of the lock. How the whole arrangement can be easily mounted upon any ordinary front plate or escutcheon will be easily understood from the following specification, wherein I explain such features, and also explain the preferred details of construction and operation of my specific preferred form of mechanism embodying my invention.

For the purpose of this specification, I have illustrated a preferred form of mechanism in the accompanying drawings, in which Figure 1 is a longitudinal section of my improved mechanism in its preferred form; Fig. 2 is a cross section taken on line 2—2 of Fig. 1; and Fig. 3 is a cross section taken on line 3—3 of Fig. 1.

In the drawings the numeral 10 designates a usual square lock-operating shaft which extends into a permutation or combination lock and connects with the tumblers thereof for the purpose of rotating them, etc. The particular construction of such a permutation lock is of no consequence whatever in my present invention, because my indexing mechanism is applicable to any kind of lock whose operation depends upon the measured rotation of such a shaft as shown at 10. In most locks a squared shaft is used, such as illustrated. The outer end of this squared shaft 10 I preferably screw thread, as

shown at 11, and screw this screw threaded end of the shaft into an internally threaded sleeve 12 which carries the hollow knob 13. The shaft 10 may be adjusted as to longitudinal position in the sleeve 12 by screwing it back and forth in the sleeve; and the shaft and sleeve may also be set in any relative rotational position by rotating the knob 13 and the sleeve 12 on the shaft 10 and then screwing the expansion screw 14 tightly into the position in the end of the shaft; the end of the shaft being split as shown at 15 to allow its expansion when tapered screw 14 is screwed home. Expansion of the end 15 of the split shaft will lock the split shaft and sleeve 12 together in any desired relative position.

The knob 13 may preferably be formed in the configuration shown, with a front web or flange 20, carrying a rearwardly extending rim 21. The interior surface 22 of this rim is preferably accurately machined so as to receive the indexing rings 23, 24 and 25. These indexing rings are preferably made as separate pieces and may be forced into the rim 21, or otherwise set in the knob; so that, to all intents and purposes, they become a part of the knob and rotate therewith. Although it is of course possible to make these indexing rings integrally with the knob itself, I prefer to make them separately as they can thus be made of a hard and durable material, while the knob may be made of a material which may, or may not, have such qualities. These indexing rings 23, 24 and 25 lie alongside each other in a co-axial arrangement; and their inner peripheries are provided with notches. For instance, the indexing ring 23 may have fifty internal notches 26; indexing ring 24 may have ten internal notches 26^a; and indexing ring 25 may have one internal notch 26^b.

The knob sleeve 12 is rotatably mounted in a stationary bearing sleeve 30. This stationary bearing sleeve may be mounted upon the front plate or escutcheon 31 of the lock in any desired manner; but a simple and effective manner is to provide the bearing sleeve 30 with a base flange 32 which bears against the face of the plate 31, the sleeve extending on through the plate 31 and being provided with a nut 33 on its rear end. With this kind of mounting, it will be seen that it is only necessary, in any front plate or escutcheon of any character, to have an opening through which the bearing sleeve 30 may be passed. Said opening may be, and is in effect, merely an enlargement of the opening through which the shaft 10 passes in any usual lock construction; so it will be seen that my indexing attachment, in its preferred form, may be very easily attached to any kind of a front plate or escutcheon without any material modification therein. This

is an important feature flowing from the fact that the mechanism is all contained in the knob-contained in a part exterior of the lock and only needing the simple connection to the lock or front plate. 70

This bearing sleeve 30 carries a disk or circular flange 35 which closes the back end of the hollow knob 13. The sleeve 30 extends on into the hollow knob forward of the flange 35, as indicated at 30^a; and at one side it has a flat surface formed thereon, as indicated at 40. A movable block 41 has one end bearing upon, or near, the flat surface 40, and has its opposite end bearing upon or near, the inner peripheries of the indexing rings 23, 24 and 25. This block 41 has a longitudinal bore 42, carrying two balls 43 and 44 with a spring 45 between them, pushing the balls outwardly; pushing the ball 43 into engagement with the indexing notches 26, 26^a, or 26^b, and pushing the ball 44 into engagement with notches 46 in the flat surface 40. The block 41 is mounted upon a shank 50 which passes through and is journaled in the flange 35, and carries a member 51 on its outer end which may be engaged by the thumb or thumb and finger, to move the shank 50 and block 41 back and forth to and between its several positions. In the form of device herein illustrated, there are three indexing rings and therefore three positions of the block 41, corresponding to the three positions in which the ball 44 is entered in any one of the notches 46. When the ball 44 engages any one of the notches 46, then the ball 43 is in position to engage the notches in either the ring 23 or the ring 24, or the ring 25, as will readily be seen by inspection of Fig. 1. By moving the block 41 transversely with relation to the indexing rings, the ball 43 may be made to engage the notches in any one of the rings; but it will be seen that ball 43 will thus engage the notches of only one ring at a time. It is a distinctive feature of this invention that I provide a single means for engaging with the notches of the indexing rings, and provide means for moving said single member from one position to another to co-operate with one or another of the rings; such provision being made that only one indexing ring may be engaged at one time. This obviates entirely the liability of error due to the fact that more than one indexing ring might be engaged at one time. Thus, the combination of several indexing rings, or other similar members, with their notches or the like, and the means for co-operating with the indexing rings, said means being relatively movable so as to engage either only one or another of the indexing rings, is a distinctive feature of my invention. And this distinctive feature of my invention is not necessarily accompanied by the particular and specific details of the preferred 130

form shown herein. But it is also a feature of my invention that I mount an indexing mechanism within the structure of a knob, mainly for the reason that such a structure 5 forms a complete and self-contained unit which may be easily adapted or attached to any existing type of permutation lock; and I do prefer to make the specific combination herein shown, of the kind of indexing mechanism herein described mounted within the knob structure. In any case, whether the mechanism is contained within a knob or not, it is operable with the use of one hand alone. It will be noted that, due to the action 10 of the ball 44 in the notches 46, the block 41 will remain or be retained in whichever one of its positions it is placed; it is not necessary for one hand to be used to hold the member 51 in any one position while the 15 knob is manipulated with the other hand. The member 51 may be moved to any one of its various positions, and then the same hand may be used to manipulate the knob, then the member 51 may be moved again, and then the knob manipulated again, and so on, 20 until the complete manipulation is finished. For instance, say that it is desired, as a part of a complete manipulation, to turn the mechanism from zero position around to the 25 right to position thirty eight. The zero position is ascertained by engagement of ball 43 in the single notch 26^a, which notch is set in correct position relative to the mechanism of the lock by adjusting the sleeve 12 on the 30 shaft 10. The zero position having been ascertained, then the block 41 is moved over to such position that the ball 43 will engage in a notch 26^a of ring 24; the rings 23 and 24 being so set that the notch 26^a comes opposite a notch 26^a. Then the knob is turned 35 until seven engagements of ball 43 with notches 26^a have occurred. This brings the mechanism to position thirty-five (there being a notch 26^a opposite every fifth notch 26 in ring 23). Then the block 41 is moved to 40 position to engage ball 43 in the notch 26 which then stands opposite, and the knob is turned through three more notch engagements, reaching position thirty-eight. All 45 this may be done with a single hand, as hereinbefore explained.

Having described a preferred form of my invention, I claim:

1. Indexing mechanism, embodying a plurality of indexing members movable together and having indexing notches at different spacings on the several members, and a single coöperating indexing member adapted to coöperate with any one of the movable 55 members.

2. Indexing mechanism, embodying a plurality of indexing members movable together and having indexing notches at different spacings on the several members, a 60 single coöperating indexing member adapt-

ed to coöperate with any one of the movable members to indicate relative movement thereof by sense of touch, and means to hold said coöperating member in position to coöperate with any one of the movable 70 members when once placed in such position by manual action.

3. Indexing mechanism, embodying a plurality of rotatable notched indexing members movable together and having indexing 75 notches at different spacings on the several members, and a single coöperating movable indexing member adapted to coöperate with any one of the rotatable members.

4. Indexing mechanism, embodying a plurality of notched circular members lying side by side, the notches in said members being at different spacings on the several members, a single coöperating indexing member adapted to coöperate with the several notched members, means to cause rotation of all the notched members relative to the coöperating member, and means to cause lateral adjustment of the coöperating member to coöperate with any one of the 80 notched members.

5. Indexing mechanism, embodying a plurality of co-axial rotatable notched disks lying side by side, said disks being rotatable together and having their notches at different spacings in the several disks, and a single transversely movable coöperating indexing member adapted to coöperate with any one of the notched disks.

6. Indexing mechanism, embodying a plurality of co-axial rotatable notched disks lying side by side, said disks being rotatable together and having their notches at different spacings in the several disks, a single transversely movable coöperating indexing member adapted to coöperate with any one of the notched disks, and means to hold said transversely movable member in position to coöperate with any one of the disks.

7. Indexing mechanism embodying a plurality of co-axial rotatable notched disks lying side by side, a stationary surface having a line of notches therein with one notch in the plane of each of the disks, a transversely movable block between the stationary surface and the disks, and oppositely pressed balls carried by the block one to engage said surface notches and the other to engage the disk notches.

8. Indexing mechanism, embodying a hollow rotatable knob, a plurality of indexing disks carried in said knob, a stationary closure for one side of the knob, and indexing means carried on said closure to selectively coöperatively engage with either of the indexing disks.

9. Indexing mechanism, embodying a hollow rotatable knob carrying circumferentially arranged indexing notches in its interior, a stationary closure for one side of 130

the knob, and indexing means carried by said closure to co-operatively engage with the indexing notches.

10. Indexing mechanism, embodying a stationary bearing sleeve, a knob sleeve journaled therein, a hollow knob on the knob sleeve and having interior indexing notches, and indexing means carried by the stationary bearing sleeve to co-operate with the indexing notches.

11. Indexing mechanism, embodying a stationary bearing sleeve, a knob sleeve journaled therein, a hollow knob on the knob sleeve, a plurality of indexing rings in the hollow knob, said rings being peripherally notched; a flange carried by the bearing sleeve and acting as a closure for the back side of the knob, and movable means carried by the flange adapted to engage the notches of any one of the indexing rings.

12. Indexing mechanism, embodying a stationary bearing sleeve, a knob sleeve journaled therein, a hollow knob on the knob sleeve, a plurality of indexing rings in the hollow knob, said rings being peripherally notched; a flange carried by the bearing sleeve and acting as a closure for the back side of the knob, a single movable means carried by the flange and adapted to engage the notches of any one of the indexing rings, and means to detain the said movable means in position to engage the notches of any single one of the indexing rings.

13. Indexing mechanism, embodying a stationary bearing sleeve adapted to be mounted upon a lock plate or the like, a knob sleeve journaled therein, a hollow knob on the knob sleeve, a plurality of indexing rings

carried within the knob and having notches on their inner peripheries, said indexing rings lying alongside each other in a co-axial arrangement, a flange carried by the bearing sleeve and acting as a closure for the back side of the knob, a single movable means carried by the flange and adapted to engage the notches of any one of the indexing rings, and means to detain said movable means in position to engage the notches of any single one of the indexing rings.

14. Indexing mechanism embodying a plurality of co-axial notched disks rotatable together, one of said disks being notched in regular spacings, and the others being notched in spacings which are multiples of the spacings on the first mentioned disk, and a single co-operating indexing member movable to co-operate with any one of the disks.

15. Indexing mechanism, embodying a hollow rotatable knob, a plurality of co-axial notched disks fixed therein and rotatable together therewith, one of said disks being notched in regular spacings, and the others being notched in spacings which are multiples of the spacings on the first mentioned disk, a stationary member on which the knob is mounted, and a single co-operating indexing member mounted on said member and movable to co-operate with any one of the disks.

In witness that I claim the foregoing I have hereunto subscribed my name this 13th day of January, 1917.

ERNEST G. ELDRIDGE.
